UNITED STATES PATENT OFFICE

ALBERT D. TRENOR, OF GLOUCESTER, MASSACHUSETTS, ASSIGNOR TO JOHN HAYS HAMMOND, JR., OF GLOUCESTER, MASSACHUSETTS

CLOSURE FOR MUSICAL INSTRUMENTS

Application filed September 24, 1929. Serial No. 394,754.

The invention relates to musical instruments and more particularly to a novel means of lifting the closure of a piano.

The invention provides the lifting of the closure of a piano while maintaining said closure in a horizontal position. This obviates the necessity of disturbing such objects as vases, pictures etc., which may be resting thereon.

10 The invention provides supporting members upon which rest the closure and means are provided for translating said members in a vertical direction. In a concrete exemplification of the invention a handle is provided 15 with means for translating said supports in a vertical direction in response to the actuation of said handle.

The invention is described as applied to a piano but it is obvious that it may be equally 20 applied to any instrument such as a radio in which it may be desirable to raise the cover thereof without disturbing the objects resting thereon.

25 The invention also consists in certain new and original features of construction and combinations of parts hereinafter set forth and claimed.

Although the novel features which are believed to be characteristic of this invention 30 will be particularly pointed out in the claims appended hereto, the invention itself, as to its objects and advantages, the mode of its operation and the manner of its organization may be better understood by referring to the 35 following description taken in connection with the accompanying drawings forming a part thereof, in which

Fig. 1 is a front elevation showing this 40 system as applied to a grand piano;

Fig. 2 is a bottom plan view of the mechanism shown in Fig. 1; and

Fig. 3 is a section taken on line 3—3 of Fig. 2.

Like reference characters denote like parts 45 in the several figures of the drawings.

In the following description and in the claims parts will be identified by specific names for convenience, but they are intended 50 to be as generic in their application to similar parts as the art will permit.

The system is shown as applied to a grand piano 10, which is provided with the usual casing 9 and pedal mechanism 11, and which is supported by three legs 12, 13 and 14. The casing 9 is provided with a top closure 15, 55 which is supported by three supporting members in the form of rods 16, 17 and 18. Each of these rods is provided at its lower end with a threaded section 20, which in the case of the rod 18 is a left hand thread, and in the rods 16 and 17 is a right hand thread. Each of these rods screws into a sleeve member 21, which is rotatably mounted in a bearing 22 carried by a frame of the piano 10. Rigidly secured to the lower part of each member 21, 55 is a bevel gear 23, which meshes with bevel pinions 24, carried on three shafts 25, 26 and 27. The shafts 25 and 26 are mounted for rotation in bearings 28, and the shaft 27 passes through the leg 14 in which it is suitably mounted for rotation. To the end of the shaft 27 is secured a handle 30.

In the operation in the form of invention shown in Figs. 1, 2 and 3, when it is desired to lift the lid of the piano 15, the handle 30 is rotated in a clockwise direction as seen in Fig. 1. This rotates the gear 23 in a clockwise direction, and by means of the pinions 24 and the shafts 25 and 26, rotates the other two gears 23 in counter-clockwise directions. 60 This causes the members 21 associated with the shafts 18, 16 and 17 to be rotated in corresponding directions, which by means of the threads cut on the rods 18, 16 and 17 cause these rods to be elevated at an equal speed 65 thus lifting the top 15 at a uniform rate and keeping it always in a horizontal position.

When it is desired to lower the top, the handle 30 is rotated in a counter-clockwise direction thus reversing the motion of the 70 parts described, and causing the top 15 to be lowered at a uniform rate until it is resting upon the top of the piano 10.

In this way a very simple and effective means is provided for translating the closure 75 15 without disturbing the objects resting thereon.

While certain novel features of the invention have been shown and described and are pointed out in the annexed claims, it will be 80

understood that various omissions, substitutions and changes in the forms and details of the device illustrated and in its operation may be made by those skilled in the art without departing from the spirit of the invention.

What is claimed is:

1. In a piano, a casing forming a sound chamber, a variable closure and means for moving said closure for said chamber in substantially parallel planes for varying the extent of opening of said chamber and controlling the emission of sound therefrom.
2. In a musical instrument, a casing forming a sound chamber, a variable closure therefor and means for moving said closure for varying the opening of said chamber and controlling the emission of sound therefrom while maintaining the same in a plane parallel to its closed position.
3. In a piano, a casing forming a sound chamber, a closure, supporting members for supporting said closure, and means for relatively elevating said supporting members in a vertical direction for varying the opening of said chamber and controlling the emission of sound therefrom.
4. In a piano, a casing forming a sound chamber, a closure, supporting members for supporting said closure, a handle, and means for elevating said supporting member in a vertical direction in response to the actuation of said handle whereby the opening of said chamber is varied for controlling the emission of sound therefrom.
5. In a piano, a casing forming a sound chamber, a closure, a supporting member for said closure said supporting member having a portion thereof threaded, a threaded sleeve encircling said threaded portion and means for rotating said sleeve whereby said member will be elevated axially of said sleeve whereby the opening of said chamber is varied for controlling the emission of sound therefrom.
6. In a piano, a casing forming a sound chamber, a closure, supporting members disposed in spaced relationship and adapted to support said closure, said supporting member having a portion thereof threaded, a threaded sleeve encircling said threaded portion, gears secured to said sleeves, a handle, a driving gear secured to said handle and meshing with one of said gears and means for rotating the threaded sleeves in response to the actuation of the handle whereby said supporting members are translated axially of said sleeves whereby the opening of said chamber is varied for controlling the emission of sound therefrom.

In testimony whereof I have hereunto set my hand.

ALBERT D. TRENOR.
